ATTORNEY

UNITED STATES PATENT OFFICE.

JOSEPH S. THOMPSON, OF SAN FRANCISCO, CALIFORNIA.

ELECTRIC SWITCH.

Application filed December 10, 1923. Serial No. 679,760.

To all whom it may concern:

Be it known that I, JOSEPH S. THOMPSON, a citizen of the United States, residing in the city and county of San Francisco, in the State of California, have invented a new and useful Improvement in Electric Switches, of which the following is a specification.

My invention relates to electric switches and particularly to disconnecting switches for high voltage lines, and its object is to provide a simple easily operated switch, with switch blades operated in a vertical plane in alignment with the axis of the supporting insulators, and with a positive operation of the blade by means of the rotation of the blade supporting insulator.

I attain this object by the device described in the specifications and claims appended hereto. The features of construction and mode of operation are illustrated in the accompanying drawings which show the preferred embodiment of my invention and in which—

Figure I is a side elevation of a switch embodying the novel features of my invention, shown in the closed position. Figure II is a plan view of the portion of the switch supported on the rotating insulator, and Figure III is a sectional view on line 3 of Figure I of the assembly of bearing, trunnion, shaft, bevel gears and insulator cap as shown in plan view in Figure II. Similar numbers refer to similar parts in the three views.

In my design, 1 is a suitable supporting base; 2 is an insulator fixedly attached thereto; 3 is a bearing; 4 is a second insulator capable of rotating in the bearing 3, preferably by means of a lever 5; 6 is a third insulator fixedly attached to the base 1; 7 is a contact, of any suitable design to receive a switch blade, fixed in position on the insulator 2; 8 is a switch blade of suitable design to which is firmly attached a bevel gear 9, which co-operates with a bevel gear 10, firmly attached to the rotating insulator 4; bearing 11 supports the trunnion shaft 12 of the blade 8, and is supported on the insulator 4 in such a fashion as to permit the insulator to rotate without rotating the bearing 11; and rotation of bearing 11 is prevented by the strut 13 which is fastened to the insulator 6 by some suitable means, such as the support, 14 the strut 13

and the bearing 11 forming a T-shaped structure.

In my application I do not confine myself to the operation of this switch as a single pole unit, but embody in the design the arrangement of several such units to form a multipole switch.

In the operation of my device, the rotating insulator 4 is moved through a portion of a revolution by the operation of a suitable mechanical connection such as the lever 5. The bevel gear 10 being firmly attached to the rotating insulator cooperates with the bevel gear 9 to swing the switch blade 8 in an arcual path, raising it from the contact on a radius fixed by the shaft 12 and so disconnecting the electric circuit. Rotation of the insulator in the opposite direction accomplishes the closing of the switch.

I regard this as an improvement over existing designs, in that the rotation of the insulator directly transmits the desired motion to the blade, the third insulator merely acting as a steadyng member to prevent the group rotation of the blade and bevel gear in relation to, and away from alignment with the fixed contact, thus permitting the support of choke coils, fuse tubes and other auxiliary apparatus upon the fixed insulator 6.

I do not confine myself to the precise mechanical details shown in the drawings attached, but intend in my claims to cover all changes and modifications which may still embody the novel features of my device.

What I claim is:

1. In a circuit controller, a rotary insulator, a blade rotatable about an axis at an angle to that of the insulator, and means for transmitting the motion of the insulator to the blade, including a stationary bearing on which the blade is pivoted, said bearing having an aperture accommodating a portion of the insulator rotating structure, a shaft for the blade carried by the bearing, a strut engaging the bearing for holding it against movement, a bevel gear on the rotary insulator and a gear on said shaft outside of the bearing in mesh with said bevel gear.

2. In a circuit controller, a rotatable insulating standard, said standard having a projection at one end, a stationary bearing

- having an aperture engaged by said projection, a shaft projecting beyond said bearing at both ends, and having an axis at an angle to that of the standard, a stationary insulator, a strut extending between said insulator and the bearing, a bifurcated contact blade mounted on the shaft, and a pair of intermeshing bevel gears, one supported on the blade coaxially with the shaft and 10 outside of the bearing, and the other on the rotating standard and coaxially therewith.
3. In a circuit controller, a stationary insulator, a T-shaped strut fixed thereon having an aperture, a rotary insulator having 15 a projection extending into said aperture, a shaft within the cross-piece of said T-shaped strut positioned at an angle to the axis of said rotary insulator, a bifurcated blade mounted on said shaft and means for transmitting the motion of said rotary insulator to said blade.
4. In a circuit controller, a stationary insulator, a T-shaped strut fixed thereon having an aperture, a rotary insulator having a projection extending into said aperture, a shaft within the cross-piece of said T-shaped strut positioned at an angle to the axis of said rotary insulator, a bifurcated blade mounted on said shaft and means for transmitting the motion of said rotary insulator to said blade, comprising a bevel gear on the rotary insulator and a gear on one end of said shaft in mesh with said bevel gear.

In witness whereof, I have hereunto set my hand this 16th day of November, 1923.

JOSEPH S. THOMPSON.
